Patented Dec. 3, 1935

UNITED STATES PATENT OFFICE

2,022,860

STABILIZED HYDROGEN PEROXIDE
COMPOSITION

Albert Kunz, Naples, Italy

No Drawing. Application March 13, 1935,
Serial No. 10,913

2 Claims. (Cl. 23—251)

Hydrogen peroxide solutions, as is well known, have a tendency to deteriorate in the course of time. Many substances have been added to such solutions in the hope that they will retard such deterioration or make the solution stable, some of which have been successful to a degree in retarding the deterioration.

For special purposes, such, for example, as for the bleaching of living human hair, the hydrogen peroxide solution must be strong enough to bleach the hair and yet must not be strong enough to burn it. In view of the degree of deterioration, which is ordinarily a function of the length of time that the solution stands, the solution in the same bottle will have different degrees of effectiveness, either beneficial or harmful, depending on the time that it is used. As a result, if a solution of hydrogen peroxide is to be used immediately for such bleaching effect, it should be made up weaker than if it is to be used after a long interval of time. Consequently, there is a great deal of confusion in the hair treatment industry, due to the constantly changing strength of the solution of hydrogen peroxide, and stand-

ardized treatment in the bleaching operation is difficult, if not impossible.

I have discovered that antipyrine is an excellent stabilizer for hydrogen peroxide solutions, for general use and particularly for the special use of bleaching living human hair and for other beauty parlor purposes.

I have discovered that one-half (1/2) gram of antipyrine per liter of hydrogen peroxide solution is very effective, but this proportion may be varied without departing from the principle of the invention since the stabilizing action remains even with different amounts, although as the amount becomes too small, the stabilizing effect decreases too rapidly, while too much antipyrine present simply amounts to a waste of that material.

Having described my invention, what I claim is:

1. An aqueous solution of hydrogen peroxide stabilized with antipyrine.
2. A stable aqueous solution of hydrogen peroxide containing about one-half gram of antipyrine per litre.

ALBERT KUNZ. 25
